No. 855,925.

PATENTED JUNE 4, 1907.

L. F. BETTS.
SHEET METAL RECEPTACLE.
APPLICATION FILED SEPT. 13, 1906.

UNITED STATES PATENT OFFICE.

LEWIS F. BETTS, OF NEW YORK, N. Y., ASSIGNOR OF ONE-FOURTH TO H. BLAKE GILMORE AND ONE-FOURTH TO JOSEPH A. KENNEDY, BOTH OF BROOKLYN, NEW YORK.

SHEET-METAL RECEPTACLE.

No. 855,925.

Specification of Letters Patent.

Patented June 4, 1907.

Application filed September 13, 1906. Serial No. 334,397.

To all whom it may concern:

Be it known that I, LEWIS F. BETTS, a citizen of the United States, residing in the city of New York, borough of Brooklyn, in the county of Kings and State of New York, have invented a certain new and useful Improvement in Sheet-Metal Receptacles, of which the following is a specification.

The invention relates to sheet-metal vessels such as ash-cans, garbage-pails, stable-buckets and the like, and the object of the invention is to provide a strong serviceable receptacle which can be economically manufactured.

15 The invention consists in certain novel features and arrangements of parts and details of construction by which the above objects are attained, to be hereinafter described.

20 The accompanying drawings form a part of this specification and show the invention as applied to an ash-can.

Figure 1 is a partial side elevation and vertical section of the can. The plane of section being indicated by the line 1—1 in the succeeding figure. Fig. 2 is a horizontal section through a portion of the can, taken on the line 2—2 in Fig. 1. Fig. 3 is a vertical section showing the junction of the can-body and top-ring, and the means for attaching the stiffening-ribs to the latter. Fig. 4 is a similar view showing the can-body and bottom. Fig. 5 is a horizontal section on the line 5—5 in Fig. 1. Fig. 6 is a corresponding view on the line 6—6 in the same figure. Fig. 7 is a vertical section through the bail-ear. Fig. 8 is a side view of the bail-ear, showing the adjacent portion of the can-body in vertical section. Fig. 9 is a 35 face view of one of the handles and its attaching loop. Fig. 10 is a section showing the action of the dies in forming the top-ring and bottom from a single sheet of metal. Fig. 11 is a side view of the upper end of one 40 of the stiffening-ribs before its attachment to the top-ring.

Similar letters of reference indicate the same parts in all the figures.

45 A is the body of the can, formed of one or more pieces of sheet metal, in the form of a truncated cone. B is the bottom and C the top-ring, each of sheet metal and secured to the body as will be described. The top-ring

has a plane horizontally-disposed annular portion or rim, the outer margin of which is 55 rolled under to inclose a wire C¹ and provide a strong rounded edge, and has a downwardly projecting flange C² tapered to match to the tapered upper portion of the body and fit snugly therein. 60

The bottom B is a disk having a flaring upturned marginal flange B¹ matching to and fitting closely within the lower end of the body. Its taper holds it against passing through the smaller opening at the lower end 65 of the body and it is held against upward movement by an annular crease or bead a on the inner surface of the body immediately above the flange B¹ and produced after the insertion of the bottom. A similar crease or 70 bead a¹ at the upper end locks the body and flange C of the top-ring together.

D D are the stiffening-ribs of sheet metal formed by dies into channel-iron shape with a flange D¹ on each side, and extending vertically on the outer face of the body from the lower edge to the under face of the top-ring. There may be as many ribs D as found necessary or desirable, the drawing shows a cam having six equally spaced. 80

A¹ A² are tongues formed in the body by making angular cuts therein and bending the metal partially inclosed by the cuts slightly outwardly, and are produced in opposite pairs one above the other as shown. 85

The ribs D are attached to the body by engaging the flanges D¹ D¹ beneath the lower pair of tongues and similarly engaging the succeeding pairs of tongues as the ribs are driven toward the top-ring. The latter is 90 provided with slots c in which are received lugs D² on the ribs, which lugs are later curled about the rounded edge of the top-ring and serve to hold the ribs against withdrawal.

E E are strips of hard wood shaped to 95 match to the interior of the ribs and driven into the latter from below and extending to the top-ring. The upper end of each strip abuts against the under face of the ring, and the lower end projects a short distance below 100 the bottom B.

F is one of a pair of oppositely located handles, only one of which is shown, by which the can may be lifted, and G is a bail for like service. The handle is in the form 105 of a link and is held in the bight or loop

F¹ of a strip of metal folded upon itself and having its ends passed through a horizontal cut a² in the body, from the exterior to the interior, and again passed through a similar lower cut a³ to the exterior and the extremities folded up against the body as at F², and thus firmly secured thereto.

The bail G has a hook at each end as usual, engaged in an ear G¹ formed by bending a

- 10 strip of metal to follow the contour of one of the ribs and project from the outer face thereof in a semicircular curve. The ends of the strip are folded inward to engage the flanges D¹ of the rib. As shown in the drawings the 15 ear is stiffened by a strip of metal G² partially inclosed by the main portion of the ear but not extending beneath the flanges D¹. The bottom B is preferably slightly domed to increase its rigidity.
- 20 In assembling the parts, the top-ring and bottom are inserted in the body and the beads a a¹ produced; the ribs are then introduced, with their lugs D² in the slots c, and forced firmly home and the lugs then curled 25 about the edge of the rim, the bail-ears G¹ being located at the proper points when the ribs are inserted. The handles F are engaged as above described, and the ends F² and tongues A¹ firmly compressed by suitable 30 tools. The whole is then galvanized the melted zinc serving not only to coat the sheet metal but also to solder all the portions together and fill the joints. The wood strips E are then driven into the ribs, and the bail 35 attached to the ears.

It will be observed that the body, top-ring, bottom, and ribs, with the required cuts and slots therein, are all formed separately and mainly by dies, and are assembled without 40 rivets, and without soldering other than the galvanizing operation.

The top-ring and the bottom are preferably cut from a single sheet, as shown in Fig. 10; the bottom is produced without waste 45 from the metal within the top-ring by the annular cut indicated by the dotted lines x—x, the portions adjacent to such cut are bent by the dies to form the flanges B¹ C² and the top-ring shaped at the same time to receive the wire C¹.

The receptacle thus constructed is eminently strong and economical to manufacture, and well adapted to resist the strains due to rough handling to which articles of 55 this class are exposed. The strips of wood extending below the bottom receive the severest strains to which the can is subjected, protect that portion of the can and tend to transfer part of such strains to the top-ring and body over a considerable area of the latter.

Modifications may be made in the forms and proportions, and parts may be used without the whole.

60 The bail and handles may be attached by

other means than here shown, and either or both may be omitted if preferred.

Although I have described the invention as applied to an ash-can it will be understood that garbage-pails and stable-buckets 70 and other receptacles may be similarly constructed with such variations as may be found necessary or desirable in adapting the invention to such articles.

I claim:—

1. In a receptacle of the character set forth, a tapered body, a top-ring having a dependent annular flange received in and matching to the upper portion of said body, a bottom inserted through the upper portion of said body, an upturned annular flange on said bottom matching the taper of said body and engaged with the lower portion thereof, and annular beads in said body engaging said flanges and holding said top-ring and bottom. 85

2. In a receptacle of the character set forth, a sheet-metal body having tongues formed thereon and integral therewith, a top-ring extending beyond the periphery of said body at the top and having slots therein, stiffening-ribs of sheet-metal having flanges engaged by said tongues, and a lug at the upper end of each of said ribs received in one of said slots and joined to said top-ring by partially inclosing the edge thereof. 90

3. In a receptacle of the character set forth, a sheet-metal body having tongues formed thereon and integral therewith, a top-ring secured to the top of said body and extending beyond the periphery thereof, a stiffening-wire in said top-ring, a slot in the latter, a stiffening-rib of sheet-metal having flanges thereon engaged by said tongues, and a lug at the upper end of said rib extending through said slot and joined to said top-ring by partially inclosing the edge thereof and said stiffening-wire. 100

4. In a receptacle of the character set forth, a sheet-metal body having tongues formed thereon and integral therewith, a top-ring secured to the top of said body and extending beyond the periphery thereof, and having slots in such extended portions, hollow stiffening-ribs having flanges engaged by said tongues, and lugs on said ribs extending through said slots and secured to said top-ring, and strips of wood received in said ribs and abutting against the under face of said top-ring and projecting below said body. 115

5. In a receptacle of the character set forth, a sheet-metal body having tongues formed thereon and integral therewith, a stiffening-rib having a flange on each side thereof engaged by said tongues, and a bail-ear comprising a strip of metal having its ends folded and partially inclosing said flanges. 120

6. In a receptacle of the character set forth, a sheet-metal body having two laterally-extending cuts therein one above the other, a strip of sheet-metal folded upon itself to 130

form a bight, a handle received in said bight and secured to said body by passing the ends of said strip through one of said cuts from the exterior of said body to the interior and 5 thence through the other of said cuts from the interior to the exterior, and folding the extremities of said ends against the exterior face of said body.

In testimony that I claim the invention above set forth I affix my signature, in presence of two witnesses.

LEWIS F. BETTS.
